(57) **CLAIM**

The ornamental design for a light fixture, substantially as
shown and described.

DESCRIPTION

FIG. 1 is a perspective view of a light fixture embodying the
design of the present invention.

FIG. 2 is a front side elevational view of the light fixture
illustrated in FIG. 1.

FIG. 3 is a right side elevational view of the light fixture
shown in FIG. 1, with the left side elevational view being
identical thereto.

FIG. 4 is a back side elevational view of the light fixture
illustrated in FIG. 1.

FIG. 5 is a top view of the light fixture illustrated in FIG. 1;
and,

FIG. 6 is a bottom view of the light fixture illustrated in FIG.
1.

The broken lines are shown for illustrative purposes only
and form no part of the claimed design.
